CLAIM

The ornamental design for a identification camera for exposing X-ray films with data of patients, substantially as shown and described.

DESCRIPTION

FIG. 1 is a perspective front view of a identification camera for exposing X-ray films with data of patients, embodying our novel design;
FIG. 2 is a front view thereof;
FIG. 3 is a rear view thereof;
FIG. 4 is a top-plan view thereof;
FIG. 5 is a bottom-plan view thereof;
FIG. 6 is a right-side view thereof; and
FIG. 7 is a left-side view thereof.
